ATTORNEY

UNITED STATES PATENT OFFICE.

HENRY J. CARMODY, OF ROME, NEW YORK.

BED-CORNER.

1,173,647.

Specification of Letters Patent. Patented Feb. 29, 1916.

Application filed June 22, 1914. Serial No. 846,504.

To all whom it may concern:

Be it known that I, HENRY J. CARMODY, a citizen of the United States, residing at Rome, in the county of Oneida and State of New York, have invented certain new and useful Improvements in Bed-Corners, of which the following is a specification, reference being had therein to the accompanying drawing.

20 My invention relates to a bed corner and I declare the following to be a full, clear, concise, and exact description thereof sufficient to enable anyone skilled in the art to which it appertains to make and use the 15 same, reference being had to the accompanying drawings in which like reference characters refer to like parts throughout the specification.

The object of the invention is to provide 20 a simple, efficient bed corner adapted to permit of the reversing of the side rail, whereby the said side rail can be employed either in the regular position or in the reverse position. The latter or reverse position is 25 vantageous for the use of slats in supporting the bed springs. These objects will appear by reference to the drawings in which:

Figure 1 is a perspective view, partially 30 in section, of the bed corner, showing the side rail held in reverse position; Fig. 2 is a perspective view, partially in section, showing the side rail held in regular position; Fig. 3 is a perspective detail view of the locking piece employed, a fragmentary 35 piece of the rail being shown attached thereto; Fig. 4 is a perspective view of the frenching or member attached to the corner post of the bed, the locking piece being removed.

40 Referring more particularly to the drawings, the bed corner embodies a frenching or member 20 secured to the end post 21 at a suitable distance from the floor end thereof, and having a projecting portion 22 in which is formed a cylindrical recess 23 with an opening 24, whereby to give access 45 for the insertion in said recess 23 of the correspondingly shaped member or tongue 25 integral with the locking or corner piece 26. The corner piece 26 is beveled at 27-27, 50 whereby either of the said beveled portions may lie adjacent the beveled surface of the shoulder 28 formed upon the portion 22 of the frenching 20, in order to hold said corner piece 26 in either the position illustrated

in Fig. 1, where the side rail 29, secured to the said corner piece, is in the reversed position or in that illustrated in Fig. 2, where the side rail 29 is in the regular position. The cylindrical construction of the 60 member or tongue 25 integral with the corner piece 26 will prevent, after its insertion in the recess 23 in the portion 22 of the frenching 20, the corner piece 26 from separating longitudinally from the frenching 20 65 and the shoulder 28 of the frenching 20 will hold the corner piece 26 in elevation, whereby there is formed a secure joint that can be easily detached to reverse the disposition of the side rail 29.

Having thus described my invention, what I claim is new and desire to secure by Letters Patent is:

1. In a bed corner, a member secured to the corner post of a bed, a cylindrical recess having a constant diameter throughout its length in said member, a locking piece having beveled portions secured to the end of a side rail, a cylindrical shaped member integral with said locking piece, beveled supporting means on said first named member, said beveled portions on said locking piece adapted to abut against said means on said first named member, whereby to hold said locking piece in elevated position and the 80 member and locking piece in close contact throughout their end areas.

2. In a bed corner, a frenching secured to the corner post of a bed, a cylindrical shaped recess in said frenching, said recess having a constant diameter throughout its length, a locking piece fastened to the end of a side rail, a cylindrical shaped tongue integral with said locking piece, beveled portions on said locking piece, and shoulders formed on 90 said frenching, outside of and adjacent the lower end of said recess, said beveled portions adapted to abut against said shoulders, whereby said locking piece may be held in elevated position.

3. In a bed corner, a frenching secured to the corner post of a bed, a cylindrical shaped recess having a given diameter throughout formed in said frenching, an opening from said recess, a locking piece 105 fastened to the end of a side rail, a cylindrical shaped tongue formed upon said locking piece, beveled portions in said locking piece, and shoulders disposed outside of said recess and adjacent the lower end thereof,

said beveled portions adapted to abut against said shoulders, whereby to hold said side rail in elevated position.

4. In a bed corner, a frenching secured to the corner post of a bed, a cylindrical shaped recess having a given diameter throughout its length formed in said frenching, an opening leading from said recess, a locking piece fastened to the end of a side rail, a cylindrical shaped tongue having a given diameter throughout its length formed integral with said locking piece, shoulders formed on said frenching, outside of said re-

cess and adjacent the lower end thereof, and beveled portions formed in said locking 15 piece adjacent the upper and lower ends of said tongue, said beveled portions adapted to abut against said shoulders, whereby to hold said side rail in elevated position.

In testimony whereof I have affixed my 20 signature in the presence of two witnesses.

HENRY J. CARMODY.
